ALEXANDER MACLEOD, OF WAVERLEY, MASSACHUSETTS, ASSIGNOR OF ONE-HALF TO
J. LINFIELD DAMON, JR., OF BROOKLINE, MASSACHUSETTS.

ELEVATOR-GATE OPERATING AND LOCKING MECHANISM.

1,160,520.

Specification of Letters Patent. Patented Nov. 16, 1915.

Application filed January 20, 1915. Serial No. 3,351.

To all whom it may concern:

Be it known that I, ALEXANDER MACLEOD, a subject of the King of Great Britain, residing at Waverley, county of Middlesex, State of Massachusetts, have invented an Improvement in Elevator-Gate Operating and Locking Mechanism, of which the following description, in connection with the accompanying drawing, is a specification, like characters on the drawing representing like parts.

This invention relates to elevator gates of that type which are opened and closed by a vertical movement and which are operated by the elevator as it approaches and leaves a landing, and the object of the invention is to provide a novel gate-operating mechanism by which when the gate is closed it will be locked from being opened by pressure applied thereto, but can be freely opened by movement of the elevator in usual manner.

In order to give an understanding of my invention I have illustrated herein a selected embodiment thereof which will now be described, after which the novel features will be pointed out in the appended claims.

Figure 1 is a perspective fragmentary view showing a portion of an elevator well 30 with a portion of the elevator therein and illustrating my improved elevator-gate-operating mechanism; Fig. 2 is an enlarged section on the line $\alpha-\alpha$; Fig. 1; Fig. 3 is a fragmentary perspective view showing a connection between the gate-controlling ropes and the gate-operating chain; Fig. 4 is a fragmentary perspective view showing one of the links of the chain and a portion of the cam carried by the elevator by which 40 the gate is operated; Fig. 5 is a vertical sectional view showing the operation of the device.

I have shown at 1 a portion of an elevator well, in which an ordinary freight elevator 45 2 is operating, and at 3 and 4 I have illustrated different landings or floors leading to the elevator well. Each landing or floor is provided with a gate 5 of the rising and falling type, and means are provided whereby 50 as the elevator approaches the landing from either direction the gate 5 will be automatically raised. The means herein shown is of the familiar endless chain gate operating type and comprises an endless chain 55 gate-operating member 6 passing around

two pulleys or wheels 9 and 10 secured to the wall of the elevator well and provided with projections 7 and 8 which are adapted to be engaged by lugs or projections 30 and 31 carried by the elevator 2 as the latter 60 rises and falls.

The gate-operating member 6 will preferably be in the form of a sprocket chain, and the members 9 and 10 in the form of sprocket wheels. This sprocket chain is connected to the elevator gate by means of a flexible gate-operating connection 11 in the form of a rope, chain or cord, which passes over suitable direction pulleys 12, and is connected to the gate 5 in any suitable way. 70 The above construction is more or less commonly used as a means for operating elevator gates, and in the operation thereof when the elevator is moving up to a landing, a projection thereon will engage the projection 8 on the sprocket chain and move the chain in the direction of the arrows Fig. 1, and since the flexible connection 11 is secured to the chain such connection will be drawn on thereby raising the gate. When 80 the elevator is descending a projection thereon will engage the projection 7 and thus give the chain the same movement which will open the gate. In devices of this nature as heretofore made it is possible for a person 85 to raise the gate 5 by hand, for the flexible connection 11 will permit of this movement.

My invention is an improvement over such constructions in that it provides means for preventing the gate 5 from being raised by any upward pressure applied thereto, while permitting the gate to be raised freely by the movement of the elevator. I accomplish this result herein by means of a gate locking 90 flexible connection 13 which is secured to the gate in any suitable way, as at 14, and which passes downwardly from the gate and around direction pulleys 15 and thence to the gate-operating member 6, said connection 13 being secured to the gate-operating member 6 at a point 16 so located that when the gate is closed said point of attachment 16 will be at the rear of a vertical line through the sprocket wheels 9 and 10 and in a position to tend to move the chain 6 in a direction opposite to that indicated by the arrows in Fig. 1. When, therefore, the gate is closed, as shown in Fig. 1, any upward lifting force applied to the gate 5 will tend 105 through the connection 13 to move the chain 110

6 in a direction opposite to that indicated by the arrows in Fig. 1. A suitable stop is provided which prevents such backward movement of the chain 6 while freely permitting the forward movement given to it by the elevator. Therefore, this simple expedient locks the gate from being opened while lifting on it, while permitting the gate to be freely opened by the elevator. While 10 any suitable means of securing the connections 11 and 13 to the chain 6 and of preventing backward movement of the chain may be employed, the construction illustrated herein has been found to be eminently practical. One of the links, to wit: the link 17 of the chain 6, is provided with two ears 18 which sustain a pin 19 to which the end of the cord or connection 11 is secured. An adjacent link 20 is provided at one side 15 with an ear or flange 21 to which the connection 13 is secured, as clearly seen in Fig. 3. The construction of the chain and of the connections 11 and 13 is such that when the gate is closed, as shown in Fig. 1, the 20 point of connection between the gate-operating rope 11 and the chain is vertically over the axes of the sprocket wheels 9 and 10, while the point of connection 16 between the gate-locking member 13 and the chain will be at one side of the vertical line.

The sprocket wheels 9 and 10 are herein shown as secured to a supporting member 22 having a channel shape, said member in turn being fastened in any suitable way to 35 the wall of the elevator well. The side flanges 23 of the channel-shaped supporting member are cut away opposite the sprocket wheels 9 and 10, as at 24, to allow the runs of the chain 6 to pass therethrough, said 40 runs of the chain operating on the outside of the flanges 23. This supporting member 22 is provided with a stop pin 25, the length of which is less than the width of the chain, so that said pin partially overlies the chain 45 6, as shown in Fig. 2. This stop pin 25 is located in a position to engage one of the ears or flanges 18 when the gate is closed, as shown in Fig. 1, and thus it prevents the chain from being moved backwardly or in 50 a direction opposite to that indicated by the arrows in Fig. 1. The length of the locking pin 25 is such, however, that the ear or flange 21 can move past the same since the latter is on the outside edge of the chain. 55 Hence when the gate closes the ear 21 will move by the pin 25, but the latter will be brought into engagement with the inside ear or flange 18 and thus limit the backward movement of the chain.

60 The projections 30 and 31 carried by the elevator and by which the chain 6 is operated present the projecting portion 33 adapted to engage the projection 7 or 8 extending from the chain and the cam surface 34 situated at one side of the projec-

tion. The projections 7 and 8 on the chain are formed on certain links 35 of the chain, and each of these links is provided with a laterally-extending flange 36 which stands in line with and engages the cam surface 34 70 as the elevator moves up or down.

In the operation of the device the chain 6 extends along one side of the cam surface 34, as shown in dotted lines Fig. 4, while the projection 33 is in a position to engage the 75 projection 8 of the link 35. When, therefore, the elevator moves upwardly the projection 33 will strike the projection 8 on the chain link, while the flange 36 will lie flatly on the portion 39 at the upper end of the 80 member 30. Because of this the chain link will be held in its vertical position and prevented from being thrown into such an inclined position as would tend to allow the projection 8 to slip off from the projection 85 33. When the projection 8 reaches the upper end of the chain and begins to pass around the pulley 7 then the flange 36 will move down over the inclined surface 34, and when the projection 8 has reached the position shown in Fig. 5 the flange 36 will be in engagement with the vertical portion 38 of the cam surface.

The two projections 7 and 8 are so placed on the sprocket chain that when the projection 8 is directly over the center of the sprocket wheel 9 the projection 7 will be directly under the center of the sprocket wheel 10, as seen clearly in Fig. 5. The two operating lugs 30 and 31 are also so positioned that when the upper lug 30 is just leaving the flange 36 of the projection 8 on the chain the lower lug 31 will be moving into engagement with the flange 36 of the other projection 7 on the chain all as shown 100 in Fig. 5. Hence as the elevator continues 105 its upward movement and the lug 30 passes out of engagement with the projection 8 the weight of the gate 5 will hold the projection 7 in engagement with the lug 31, which lug 110 will control the closing movement of the gate.

I claim:

1. In an elevator-gate-operating device, the combination with a vertically-moving elevator gate, of an endless gate-operating chain connected to the gate, means to move the chain forwardly by the movement of an elevator and thereby raise the gate, a stop to prevent backward movement of the chain from its initial position, and a gate-locking connection between said gate and chain by which when the gate is closed lifting pressure applied to the gate will tend to move the chain backwardly.

2. In an elevator-gate-operating device, the combination with a vertically-moving elevator gate, of an endless gate-operating chain adapted to be actuated by the movement of an elevator, a gate-opening connec-

tion between said chain and gate, and a gate-locking connection between said chain and gate and by which the gate is locked when it is closed.

5 3. In an elevator gate-operating device, the combination with a vertically-moving gate, of an endless gate-operating chain secured to the wall of an elevator well, sprocket wheels over which said chain runs, 10 said chain having projections extending therefrom which are engaged by an elevator, a gate-opening connection from said chain to the gate, a gate-locking connection extending from said gate to said chain and secured thereto at a point in the rear of the 15 point of attachment with the gate-opening connection, and means to prevent backward movement of said chain.

4. In an elevator gate-operating device, 20 the combination with an elevator well provided with a landing, of a vertically-moving elevator gate, an endless-gate-operating chain, sprocket wheels secured to the wall of the elevator well and over which the chain 25 passes, a gate opening and a gate-locking connection extending from said gate to said chain, means to move the chain in a forward direction by the movement of an elevator thereby to open the gate, the point of attachment 30 between the gate-locking connection and said chain being such that when the gate is closed vertical movement of the gate will tend to move the chain backwardly, and means to limit such backward movement.

35 5. In an elevator gate operating device, the combination with an elevator well having a landing, of a vertically-moving gate for said landing, an endless-gate-operating chain, sprocket wheels secured to the wall of 40 the elevator well and around which said chain passes, means to move the chain forwardly by the movement of the elevator in

the well, a gate-opening connection leading from the gate to the chain, a gate-locking connection also leading from the gate to the 45 chain, the point of attachment of said gate-locking connection with the chain being on the rear side of a line extending through the axes of the sprocket wheel when the gate is closed, and a stop to limit backward movement of the gate.

50 6. In an elevator gate-operating device, the combination with a vertically-moving elevator gate, of an endless gate-operating chain connected to the gate, one link of said chain being provided with a finger and with a laterally-extending flange, and an elevator having a projection to engage said finger thereby to operate the chain, and a rest on 55 which the flange of the link is sustained 60 whereby the latter is maintained in its vertical position.

65 7. In an elevator gate-operating device, the combination with a vertically-moving gate, of an endless-gate-operating chain connected to the gate, sprocket wheels around which said chain passes, one of the links of the chain having a finger extending therefrom in line with the chain and also a laterally-extending flange at one side of the 70 chain, an elevator, a projection extending therefrom to engage said finger thereby to operate the chain, a rest portion to receive the flange thereby to hold the link in vertical position, and a cam portion 34 over which the flange passes when the link moves around 75 one of the sprocket wheels.

In testimony whereof, I have signed my name to this specification, in the presence of two subscribing witnesses.

ALEXANDER MACLEOD.

It is hereby certified that in Letters Patent No. 1,160,520, granted November 16, 1915, upon the application of Alexander MacLeod, of Waverley, Massachusetts, for an improvement in "Elevator-Gate Operating and Locking Mechanism," an error appears in the printed specification requiring correction as follows: Page 3, line 7, claim 3, for the word "andless" read *endless*; and that the said Letters Patent should be read with this correction therein that the same may conform to the record of the case in the Patent Office.

Signed and sealed this 14th day of December, A. D., 1915.

[SEAL.]

R. F. WHITEHEAD,

Acting Commissioner of Patents.
